SCALP MEDICATOR

James A. Sluss, Salem, Va.

Application July 14, 1941, Serial No. 402,375

2 Claims. (Cl. 132—13)

This invention relates to applicators and, more particularly, to an improved scalp medicator.

One object of the invention is to provide a scalp medicator by the use of which it will be possible to distribute liquid medicaments to the scalp for treating said scalp and improving the condition of the hair.

Another object of the invention is to provide a device of this character employing a handle which defines a reservoir for containing the medicament.

Another object of the invention is to provide a scalp medicator wherein improved valve means is employed for controlling flow of the liquid medicament from the reservoir.

Still another object of the invention is to provide, in a device of the character mentioned, valve means in the reservoir which will be movable for preventing an air lock, with the result that free flow of the liquid medicament from the reservoir will be assured.

A still further object of the invention is to provide a scalp medicator having a comb formed with tines, said tines being hollow and having discharge openings formed in their side walls so that clogging will be prevented.

And still another object of the invention is to provide a scalp medicator which is simple in construction and which will be highly efficient in use.

Other objects of the invention, not specifically mentioned hereinbefore, will become apparent during the course of the following description.

In the drawing forming a part of my application:

Figure 1 is a side elevation of my improved scalp medicator.

Figure 2 is a longitudinal sectional view of the device.

Figure 3 is an enlarged detail sectional view on the line 3—3 of Figure 1.

Figure 4 is an enlarged detail sectional view showing the control valve.

Figure 5 is a vertical sectional view on the line 5—5 of Figure 4.

Figure 6 is a horizontal sectional view on the line 6—6 of Figure 5.

Figure 7 is a horizontal sectional view similar to Figure 6 but showing the control valve in closed position.

Figure 8 is an enlarged detail vertical sectional view showing the air valve as it would appear in open position,

Figure 9 is an enlarged detail vertical sectional view showing the air valve in closed position.

Figure 10 is a detail transverse sectional view on the line 10—10 of Figure 8, and

Figure 11 is a detail transverse sectional view on the line 11—11 of Figure 9.

Referring now more particularly to the drawing, wherein like numerals of reference designate like parts throughout the views, the numeral 1 indicates in general the body of my improved scalp medicator. The body 1 includes a handle 2 and a comb 3. The handle 2, as best seen in Figure 2, is enlarged and is formed with a hollow interior which defines a reservoir 4. The body 1 is formed of metal, hard rubber, plastic, or other suitable material, the handle being, of course, of a shape to fit snugly in the hand of a user. Formed on the handle 2 medially of its length and width is an upstanding boss 5 which is formed with a flat upper wall 6. The boss 5 is apertured to define an inlet 7 through which medicament may be passed to the interior of the reservoir 4. Extending throughout the length of the inlet 7 and communicating therewith is an arcuate groove 8, the purpose of which will be set forth in more detail hereinafter. Screwed in the inlet 7 is a plug valve 9 which is formed with a knurled head 10 having a flat under surface 11 which is engageable with the flat upper surface 6 of the boss 5 for providing an air seal. Formed in the plug valve and extending throughout its length is an arcuate groove 12 which cooperates with the groove 8 for defining an air passage 13. As seen in Figure 8, when the plug valve is unscrewed, for disposing the head 10 thereof above the flat upper surface 6 of the boss 5, the grooves 8 and 12 may be aligned for defining the air passage or vent 13. Air will flow between the boss and the head 10 and through the passage 13 to the interior of the reservoir for permitting free flow of liquid therefrom. The plug valve may be entirely removed when it is desired to add medicament to the reservoir. When the plug valve is screwed down to closed position, as shown in Figure 9, the under surface 11 of the head 10 will engage the upper surface of the boss 5 and provide a seal. As shown in Figure 11, when the head is in closed position, the grooves 8 and 12 will be out of alignment.

The comb 3 includes a head 14 which is formed with a channel 15 extending throughout its length. The channel 15 communicates with the interior of the reservoir 4 through a passage 16 between the handle 2 and said comb 3. Formed

on the head 14 are spaced tines or teeth 17 each of which is formed with a discharge passage 18 which communicates with the channel 15. As will be observed, each of the passages 18 is smaller than the channel 15. Each of the tines or teeth 17, as best seen in Figure 3, is formed with a discharge opening 19. The openings 19 are disposed at one side of the lower end portions of the teeth. The purpose of the location of the discharge openings 19 is to prevent clogging of the teeth 10 which would otherwise occur.

Formed on the body 1, between the comb 3 and the handle 2 is a boss 20 and screwed through the boss into the passage 16 is a control valve 21, said valve being formed with a knurled head 22 and, near its lower end, with a discharge opening 23. As best seen in Figures 4 through 7 of the drawing, the opening 23 is disposed so that it may be caused to align with the passage 16. More specifically, when the control valve is shifted to the position shown in Figures 4 and 6, the opening 23 will be in alignment with the passage 16 and liquid will be permitted to flow into the channel 15 and thus into the tines or teeth of the comb, for discharge from the openings 19. However, when the control valve is rotated substantially one-half turn, the opening 23 will be disposed in the position shown in Figures 5 and 7. That is to say, the opening 23 will be disposed at a right angle to the passage 16 and liquid will be 30 prevented from flowing into the channel 15.

It is believed that the operation of my invention will be clearly understood, after a reading of the foregoing. However, a brief statement is not believed to be out of place. The control valve 21 is first closed and the plug valve is removed. Medicament is poured into the reservoir 4 and the plug valve is again screwed into place. When it is desired to medicate the scalp, and thus improve the condition of the hair, the valve 21 is 35 rotated to open position for permitting medicament to pass into the channel 15 and through the teeth 17 for discharge from the openings 19. In order to insure the free flow of medicament, air is admitted to the reservoir by unscrewing the 40 plug valve and aligning the grooves 8 and 12, in the manner set forth hereinbefore.

It is desired to emphasize that, inasmuch as the discharge openings 19 are disposed at one side of the teeth 17, said openings will not readily become clogged with dandruff or the like, and thus free flow of medicament will not be obstructed.

By the use of my improved scalp medicator, it will be possible to medicate the scalp in a simple and highly efficient manner, with the result that the hair can be properly treated for keeping it in the best possible condition. My improved medicator is light in weight and simple in construction. There are but few parts to the device so that the same may be easily kept clean and otherwise in good condition.

Having thus described the invention, what is claimed as new is:

1. A device of the class described including a body having a reservoir and a boss formed with an inlet, said inlet having a groove and said boss having a flat top wall, a plug valve screwed in the inlet and having a head provided with a flat under surface adapted to engage the flat upper surface of the boss and form a seal in closed position, said plug valve having a groove and being rotatable for unseating the head from the boss and alining the grooves to provide a vent for the interior of the reservoir.

2. In a fountain comb, a handle having an internal liquid reservoir and provided with a hollow interiorly threaded boss communicating with said reservoir, the interior threads on one side of the boss being cut away to form a vertical air passage, and a combined closure plug and air vent having a threaded shank detachably engaging the threads on the boss and provided at its upper end with an enlarged head adapted to normally seat on the adjacent end of the boss and close said air passage, the threads on one side of the shank being cut away to form a vertical groove adapted to register with the air passage when the plug is rotated to unseat the head thereof thereby to permit venting of the reservoir through said vertical air passage.

JAMES A. SLUSS.
